SUCTION CLEANER

Lawrence E. Dettle, River Forest, Ill., assignor of
one-half to Ira J. Wilson, Winnetka, Ill.

Application December 2, 1940, Serial No. 368,118

2 Claims.

(CL. 15—13)

This invention relates to suction or vacuum cleaners and more particularly to the construction of the suction cleaner nozzle.

Suction cleaners commonly used comprise a suction housing provided with a mouth in the form of an elongated slot which is propelled over the surface to be cleaned, and in greater or less proximity to said surface in accordance with the setting of a provided adjustment. The suction into the nozzle is constant on both the front and rear sides thereof, although I am aware that it has heretofore been proposed to shift the entrance opening into the nozzle from front to rear and visa versa, in accordance with the direction of travel of the cleaner.

My present invention aims to improve the cleaning efficiency of devices of this character by providing a nozzle which will automatically vary both the degree of suction and the direction of air travel into the nozzle, so that intermittent suction impulses are produced which will be more effective in the removal of lint, thread, hairs and other clinging substances than the steady and uniform suction heretofore relied upon.

For the purpose of obtaining this desirable result, my invention contemplates an elongated and relatively narrow suction passage having its entrance end disposed at the lower end of the suction nozzle and comprising side walls adapted to contact the surface to be cleaned. These walls are so mounted that they may be raised and lowered in alternation relatively to the surface so as to alternately provide and obstruct an ingress slot into the suction passage alternately at the front and rear of such passage. This action produces jerky suction impulses which effectively dislodge from the surface being cleaned those substances and materials which have a tendency to cling thereto.

For the purpose of facilitating an understanding of my invention, I have illustrated on the accompanying drawing preferred embodiments thereof from which, when considered in connection with the following description, the principles of my invention and many of its attendant advantages should be readily understood and appreciated.

Referring to the drawing:

Fig. 1 is a perspective view of one form of suction cleaner embodying my invention;

Fig. 2 is a sectional view of the cleaner head taken substantially on the line 2—2 of Fig. 3;

Fig. 3 is a sectional view on the line 3—3 of Fig. 2;

Fig. 4 is a fragmentary view similar to Fig. 3 showing a modified detail;

Fig. 5 is a horizontal sectional view on the line 5—5 of Fig. 4; and

Fig. 6 is a fragmentary vertical section on the line 6—6 of Fig. 5.

Referring to the drawing more in detail, reference character 7 indicates a motor housing and 8 designates a suction fan housing attached thereto, the motor 9 and the fan rotor 11 being contained within these respective housings, as is customary.

A housing 12, sometimes called a suction nozzle, projects forwardly and downwardly from the fan housing, and, in the form shown in Figs. 1, 2 and 3, instead of terminating in a long narrow suction mouth, is made somewhat wider so that its front and rear walls 13 and 14 are spaced some distance apart and terminate some distance above the surface to be cleaned, as will be apparent from Fig. 3.

The depending portion of this housing is provided with a longitudinally extending bearing 15 in which is journaled a semi-cylindrical member 16 provided with a passage extending therethrough from top to bottom, as shown. This passage is extended downwardly between depending walls 17 and 18 formed integrally with the oscillating member 16 or attached thereto by bolts 19 or other suitable fastening means. It will be observed that the passage between these side walls is closed at the ends by end walls 21, and that the lower edges of these side walls extend downwardly below the housing walls 13 and 14 so that the edges of walls 17 and 18 may contact with the surfaces to be cleaned. The walls are positioned in the proper relation to the surface by adjustable supporting rollers 22 carrying the forward end of the cleaner.

The member 16 carrying the nozzle proper consisting of the side walls 17 and 18 and the end walls 21 is designed to be oscillated in its supporting bearing, and for this purpose one or both ends thereof is provided with an upstanding ear 23 perforated to receive the inwardly bent end of a link 24 which extends through a slot 25 in the housing end wall. This slot is closed by a plate 26 carried by the link and overlying the outer face of the slot. The opposite, inwardly bent end of the link is connected to a crank 26 carried by a shaft 27 which is journaled in a suitable bearing 28 and is provided at its inner end with a worm wheel 29 meshing with and adapted to be driven by a worm 31 mounted upon the motor shaft 32 between the

motor 8 and the fan motor 11. If preferred, the shaft 27 may be extended in the opposite direction as well and connected through a crank and link with the other end of the oscillating member 16 so that this member will be driven from both ends instead of from one end only.

When the cleaner is operated, the member 16 oscillates to swing the nozzle in opposite directions from the center full line position shown in Fig. 3 to the dotted line positions indicated. When the nozzle is in the vertical position illustrated, the lower edges of its walls contact the surface being cleaned, thereby causing a partial vacuum to be built up in the vacuum housing. When it swings to the left from this position, the lower edge of wall 17 moving upwardly in an arc withdraws from the surface, permitting a sharp inrush of air which carries with it not only the loose dirt, but any material or substance tending to cling to the surface. When the nozzle swings in the opposite direction, the wall 18 is correspondingly withdrawn from the surface, and a similar inrush of air from the opposite side of the nozzle takes place. These oscillatory movements of the nozzle are positive and continuous and are in nowise dependent upon the direction of travel of the cleaner. The movements produce a succession of air impulses or intermittent air flows into the nozzle alternately from opposite directions, which produce a superior cleaning effect to the steady air inflow obtained with ordinary nozzles.

In Figs. 4, 5 and 6, a modified form of nozzle is disclosed wherein instead of an oscillating member carrying a nozzle rigid therewith, the walls of the housing are thickened near their lower ends, as indicated by reference characters 33 and 34, and are provided with vertical guide grooves 35 in which the nozzle side walls 36 and 37 are adapted to vertically reciprocate. The reciprocating movements may be imparted to these walls in any desired manner, but, as illustrated, a lever 38 connected by links 39 and 41 to the walls is adapted to be oscillated by the link 24 to alternately raise and lower the walls 36 and 37. A plurality of levers fixed on a shaft 42 are preferably employed with this type of construction.

In this modification, the operation is similar to that above described. As the cleaner travels over the surface, the walls 36 are alternately brought

into contact with and withdrawn from the surface being cleaned, thereby producing a succession of air impulses delivered into the suction head alternately from opposite directions. The cleaning effect is similar to that of the oscillating nozzle above described.

The principle of my invention resides in a nozzle which is so manipulated that a vacuum of varying intensity is produced, and the air which carries the material to the surface being cleaned into the cleaner is delivered in a succession of impulses and alternately in opposite directions. The details of the apparatus for carrying this principle into effect as well as the mechanism for driving the same may obviously be varied within wide limits without departing from the essence of the invention as defined in the following claims.

I claim:

1. A suction cleaner comprising a nozzle housing, means for supporting said housing in spaced relation to the surface being cleaned, a nozzle mounted for oscillatory movement in said housing, including side walls having substantially parallel edges projecting below said housing, the said edges terminating in a single plane and being in position to contact the surface being cleaned, and continuously operating means for oscillating said nozzle to raise and lower said side walls in alternation during travel of the cleaner in both directions, whereby suction entrance to said nozzle is afforded alternately in opposite directions as the cleaner moves over said surface.

2. A suction cleaner comprising a nozzle housing having parallel front and rear side walls forming a mouth, means for supporting said housing in spaced relation to a surface to be cleaned, a nozzle mounted for oscillatory movement in said housing and including side walls substantially parallel with and extending below said housing walls in position to contact the surface being cleaned, and continuously operating means for oscillating said nozzle to raise and lower said side walls in alternation during travel of the cleaner in both directions to thereby alternately obstruct and open said nozzle to produce intermittent suction impulses and induce air flow alternately in opposite directions along the surface being cleaned into said nozzle.

LAWRENCE E. DETTLE.
